TROUSERS CONSTRUCTION

William Shulik, Philadelphia, Pa.

Application November 15, 1934, Serial No. 753,167

4 Claims. (Cl. 2-234)

My invention relates to certain new and useful improvements in trousers construction, and it relates more particularly to the construction of the front opening of trousers.

The object of my invention is to provide trousers construction which will be easier to produce and which will be neater in appearance and more serviceable in use, and which will be generally more desirable than the forms of construction heretofore employed.

Another object of my invention is to so construct trousers as to minimize the cost of production and to facilitate the opening and closing and to generally improve the construction.

With the above and other objects in view, my invention consists of a trousers construction in which the front flap of the opening of the trousers is formed on the inside of the same cloth as of which the garment itself is formed, that is, what is known as "self-cloth", and in which the link-carrying or scoop-carrying tapes of the closure fastener are generally concealed by the self-cloth.

My invention further relates to other novel features and details of construction, all of which will appear more fully from the following description and accompanying drawing.

I am aware that my invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Referring to the drawing in which like reference characters indicate like parts:

Figure 1 represents a fragmentary front elevational view of the front of the trousers showing the front opening thereof partly open and embodying my invention.

Figure 2 represents a generally horizontal section of the inner flap construction taken generally on line 2-2 of Figure 4.

Figure 3 represents a generally horizontal section of the outer flap construction taken generally on line 3-3 of Figure 5.

Figure 4 represents a fragmentary elevational view of the outer face of the inner flap or fly of the trousers embodying my invention, shown on a much enlarged scale.

Figure 5 represents a fragmentary elevational view of the inner face of the outer flap or fly of the trouser construction embodying my invention also shown on a similarly enlarged scale.

Figure 6 represents the juxtaposed or coacting faces of the inner and outer flaps or flies of the trousers embodying my invention, with parts broken away so as to permit the showing of the upper and lower ends of each of these members. 5

According to my invention, I provide a separate fly strip 7 of the same cloth as of which the garment is made, that is, what is generally known as "self-cloth". The fly strip 7 may be provided with a longitudinal slit generally along 10 the line 8 for a distance approximately equal to the length of the fastener tape to be used. This slit preferably terminates below the upper end of the strip 7, as for instance at 9, and may also terminate short of the lower end of said strip. A strip of lining fabric 10 is sewed to the outer border zone 11 of the slit 8 by means of a layer of sewn stitches 12, with the edge portion 13 of the lining strip 10 turned inwardly to a suitable extent as indicated particularly in Figure 3. 20

The balance of the width of the strip 10 is then extended through the slit. The tape 14 of one of the two rows of links is then also inserted in the slit 8 as indicated in Figure 3 and the cut edge or marginal zone 15 of the slit is then turned inwardly to a slight extent and the inturned edge sewed to the tape 14, the strip 10 and the inner reinforcing fly 16 of any suitable fabric or textile or other material. Thereafter the cloth strip 7 is sewed to the edge zone 17 of the front portion 18 of the trousers by means of a row of stitches 19 applied through the two marginal zones while the two cloth pieces 7 and 18 are turned inside out with respect to each other. 30

The cloth strip 7 and the front cloth portion 18 of the trousers are then folded with respect to each other, more or less about the seam formed by the stitches 19 or slightly adjacent to such seam with the outer edge 20 of the reinforcing fly 16 extending either into the fold of the cloth strip 7 or into the fold 21 of the cloth 18. Thereafter, the inner longitudinal marginal zone or portion 22 of the cloth strip 7 is sewed to the front cloth portion or panel of the trousers by means of a row of stitches 23 which may be extended through, or which may be a blind stitch invisible from the outside. 35

If desired, the edge 24 of the cloth strip 7 may be bound either by turning it in and stitching it, or by means of a serging stitch 25 as indicated in Figures 1, 3 and 5. 40

The top portion 26 of the trousers may be either of the separate waist-band construction or the integral waist-band construction. If the 55

- waist-band is integral, the outer ply waist-band extension 27 may be formed integrally with the body of the trousers, while the inner ply of the waist-band extension may be formed integrally 5 with the fabric strip 7 or it may be, and preferably is, formed of a separate piece seamed to the strip 7. In the separate waist-band construction, the strip 7 is previously extended across the separate waist band.
- 10 Likewise, the strip 7 may be extended only to approximately the juncture line between the top of the trousers and the waist band, and possibly slightly beyond, so as to be included in the seam between the waist band and the body of the 15 trousers. The inner fly, designated generally by the numeral 30, is formed of a cloth 31 which is extended under the marginal zone 32 of the right side 33 of the front of the trousers to an extent sufficient to form a seam, and said marginal zone 32 is on the other hand, turned inwardly a slight extent, as indicated particularly in Figures 2 and 4.
- The lining strip 34 is sewed to the cloth layer 31 along its marginal zone 35 as indicated particularly in Figure 2.
- 25 The tape 36 of the opposite row of links 37 is then inserted between the cloth of the body portion 33 and the cloth of the strip 31, and a single layer of sewn stitches indicated by 38 is extended through both cloth pieces of the tape 36 as well as the inturned marginal zone 39 of the 30 lining. By this means the tape 14 as well as the tape 36 are set into cloth plies and are concealed thereby, so that the two rows of links appear to 35 extend from, or to project from, opposite cloth surfaces of the same material as the body of the garment. The cloth strip 31 may be extended to the juncture line 40 of the body and waist-band 41, or it may be extended to the top 42 being then in turn seamed to the waist band along the line 43.
- 40 While the fabric strips 7 and 31 are in the preferred embodiment formed of what in the trade is generally referred to as self cloth, that 45 is, of the same cloth of which the garment is formed, yet these strips may be formed of other fabrics.
- Instead of sewing in place the tapes 14 and 50 36, already equipped with the metallic links or 55 scoops, these tapes may be sewn in place, or may otherwise be fastened to or be made a part of the garment, without any metallic links or scoops thereon, and the trousers thus more or less finished or tailored to a more or less finished 60 condition and the metallic links or scoops then applied to the marginal or zones of the tapes or similar members by clamping, swedging or by otherwise securing the links or scoops to the tape, as for instance by casting them in place in 65 suitably spaced intervals. By this method of first sewing the tape or tapes in place in the garment and then applying links or scoops to the tapes in situ, the cost of producing the garment with a slide fastener closed front is materially reduced. The application of these links or scoops to the tape in situ may be effected by any suitable or conventional apparatus adapted either to dye and coin these links and to send

them to and to clamp them onto the tape or apparatus adapted to cast individual links or scoops to the tape.

Having thus described my invention, what I hereby claim as new, and desire to secure by 5 Letters Patent, is:

1. In trousers, a front opening including two juxtaposed trousers portions adapted to be connected and disconnected from each other for closing and opening the front of the trousers, one 10 of said juxtaposed trousers portions including a layer of self-cloth longitudinally interrupted, a scoop-carrying tape of a slide fastener and a strip of lining fabric extending together through said layer of self-cloth and said line of interruption, with the tape substantially concealed behind said layer of self-cloth and with the scoops projecting externally therefrom, the lining strip overlying the outer surface of the self-cloth so as to protect the self-cloth from the 15 scoops, a line of stitching securing the tape and lining strip to the self-cloth at one side of the line of interruption, and another line of stitching securing the lining strip to the self-cloth at the other side of said line. 25

2. In trousers, a strip of self-cloth fastened to the inner face of the trousers along two spaced lines, one of which is substantially at the front opening of the garment, said strip having a slit therein, a scoop-carrying tape fastened to said strip and lying on the face thereof intermediate such strip and the trousers and so arranged that it projects through said slit and that the scoops lie on the opposite side of a portion of said strip from said tape, a backing strip extending through said slit and lying on the side of said tape toward the front of the trousers and connected to said strip of self cloth at both sides of said slit as well as to said tape on one side of the slit. 35

3. In trousers, the construction as set forth in 40 claim 2, together with a second backing strip extending between the strip of self-cloth and the front of the trousers for substantially the entire width of the strip of self-cloth and fastened to the strip of self-cloth, the backing strip 45 and the front of the trousers.

4. In trousers, a front opening including two juxtaposed trousers portions adapted to be connected and disconnected from each other for closing and opening the front of the trousers, one 50 of said juxtaposed trousers portions including a layer of self-cloth longitudinally interrupted, a scoop-carrying tape of a slide fastener and a strip of lining fabric extending together through said layer of self-cloth and said line of interruption, with the tape substantially concealed behind said layer of self-cloth and with the scoops projecting externally therefrom, the lining strip overlying the outer surface of the self-cloth so as to protect the self-cloth from the scoops, a 55 line of stitching securing the lining strip to the self-cloth at said side of the line of interruption, another line of stitching securing the tape and lining strip to the self-cloth at the opposite side of said line, and a further line of stitching on 60 the last named side of said line securing the self-cloth and lining to the trousers front. 65

WILLIAM SHULIK.
